SAFETY RAZOR CASE

Peter Paul Klepa, Los Angeles, Calif., assignor to Ever-sharp, Inc., New York, N.Y., a corporation of Delaware

Filed Sept. 30, 1960, Ser. No. 62,313

Term of patent 14 years

(Cl. D58—12)

Fig. 1

Fig. 2

Fig. 3

Fig. 4

FIG. 1 is a top plan view of a safety razor case showing my new design;

FIG. 2 is a front elevational view thereof;

FIG. 3 is a rear elevational view thereof; and

FIG. 4 is an end elevational view thereof.

The end not shown is the same as the end shown.

The dominant features of my design reside in the portions shown in full lines.

I claim:

The ornamental design for a safety razor case, substantially as shown and described.
